(57) **CLAIM**

The ornamental design for a plant cultivator, as shown and described.

DESCRIPTION

FIG. 1 is a right perspective view of the plant cultivator with its doors closed;

FIG. 2 is a left perspective view of the plant cultivator with its doors closed;

FIG. 3 is a perspective view of the plant cultivator with its doors open;

FIG. 4 is a perspective view of the plant cultivator with its doors open and its lowest grow tray pulled partially out;

FIG. 5 is a perspective view of the plant cultivator with its doors open, its lowest grow tray pulled partially out and its inserts removed;

FIG. 6 is a perspective view of the plant cultivator with its doors open and its grow trays and inserts removed;

FIG. 7 is a perspective view of the plant cultivator with its doors open and its uppermost grow tray pulled partially out;

FIG. 8 is a front elevation view of the plant cultivator with its doors closed;

FIG. 9 is a rear elevation view of the plant cultivator with its doors closed;

FIG. 10 is a right side elevation view of the plant cultivator with its doors closed, the left side elevation view being a mirror image of the right side elevation view;

FIG. 11 is a bottom elevation view of the plant cultivator with its doors closed; and,

FIG. 12 is a top elevation view of the plant cultivator with its doors closed.

The features shown in broken lines are for illustrative purposes only and form no part of the claimed design.
